[57] CLAIM

The ornamental design for a bottle or similar article, as shown and described.

DESCRIPTION

FIG. 1 is a perspective view of a bottle or similar article showing my new design;

FIG. 2 is an elevational view, the opposite side being
the same in appearance;

FIG. 3 is a top plan view;

FIG. 4 is a bottom plan view; and

FIG. 5 is an exploded elevational view thereof, partly in section.

FIG. 1

FIG. 2

FIG. 3

FIG. 5

FIG. 4
